PETER COOPER HEWITT, OF RINGWOOD MANOR, NEW JERSEY.

REFRACTING CONTAINER FOR ILLUMINATING MEANS.

1,177,325.

Specification of Letters Patent. Patented Mar. 28, 1916.

Application filed December 20, 1912. Serial No. 737,867.

To all whom it may concern:

Be it known that I, PETER COOPER HEWITT, a citizen of the United States, and resident of Ringwood Manor, in the county of Passaic and State of New Jersey, have invented certain new and useful Improvements in Refracting Containers for Illuminating Means, of which the following is a specification.

This invention has for its object the directing and diffusing of light by refraction and is applicable for use with any common source of light, such, for instance, as electric arcs, incandescent filaments or mantles, gas flames or the like. In my prior application, Serial No. 708,421, filed July 9, 1912, I have illustrated an electric incandescent lamp having the outer surface of the bulb provided with refractors in the form of depressions and elevations encircling the bulb and serving to refract a portion of the light in the direction of the ends of the bulbs which are comparatively dark in the ordinary tungsten lamp with zigzag filaments.

My present invention results from my discovery that by providing a series of refractors each with its base toward a source of light, I can so form the refractors and so position them in respect to the source of light that substantially all of the light entering the base of each refractor will be emitted, and, furthermore, will be emitted from a single outer surface of the refractor. This I accomplish by such a formation and arrangement of the refractors and such positioning of them in respect to the source of light that one portion of the light entering the base of each refractor will be reflected one or more times within the refractor and emitted from an outer surface, and another portion of the light entering the base will be reflected a greater number of times within the refractor and emitted from the same outer face as the first-mentioned portion. To this end I arrange the several refractors with respect to each other and the source of light with respect to all of them, so that the rays of light will traverse each refractor at an angle to the bisector of the outer angle of the refractor and so that the light entering the base and traversing the glass of each refractor will strike one outer surface at a

greater angle than does the light striking the other outer surface, preferably that striking the farther side being singly reflected and emitted through the nearer side, and that directly striking the nearer side will do so at a smaller angle and be reflected to the farther side and thence back and emitted from the nearer side. Thus, substantially all of the light entering the base from the source will be emitted in one direction and upon the same side of said bisectors of said outer angles.

The principle of my invention according to which the scope and reasonable equivalents thereof may be judged is best illustrated in the simplest geometrical form in which I have contemplated embodying the same, for instance, the lower portion of the container or the portion in the direction of which it is desired to direct the illumination may be approximately a hemisphere, so that the bases of the prisms may be considered as approximate planes, the transverse curvatures of the zones of each base being small. The prisms formed on the outside of such a container will be simplest when their cross-section is that of an isosceles triangle. The zones covered by the annular bases of each of the prisms will be like zones of latitude on the earth in that they have the polar diameter of the container as their common axis and the center of the hemisphere as their common center; in such case, the polar diameter will be parallel with the direction of the maximum illumination if a filament group of filaments, cylindrical mantle or the like be employed, and the equatorial diameter or plane will be at right-angles thereto.

In such an arrangement and with isosceles triangles, the source of light should be at one side of the normal to the base of each refractor and the angles to be given the exterior or light-emissive sides of the prisms will depend upon the index of refraction of the particular glass used, as, for instance, an ordinary index of refraction glass such as may be used, may be, say 1.52. In such case the angle of the sides of the refractors may be $32^{\circ} 34'$. In such case and with any source of light suitably located in the polar axis and below the equatorial plane, the

light will be, in the case of each and all refractors, emitted on the side of the prism refractor presented in the direction of the polar diameter, that is, away from the equatorial plane. As I have above explained this will be accomplished by single reflection of some of the rays and by double reflection of other rays; the rays of light entering the base of any prisms in such manner as to seek to emerge from the prism surface on the side toward the equatorial plane, will be reflected once by total reflection and will thus strike the opposite face of the prism at an angle of light emission. At the same time that portion of the light which enters the base of the prisms and traverses the glass to the outer surface and seeks to emerge from the surface directed away from the equatorial plane, will strike it at a much more acute angle than the rays first mentioned. These rays will be totally reflected, and will again traverse the glass across the prism to the surface presented toward the equatorial plane where the angle will be again found to be an angle of total reflection, but these two total reflections will have resulted in bringing the rays so nearly perpendicular to the surfaces that upon again traversing the glass and a second time approaching the outer surface presented in the direction away from the equatorial plane, the angle will be an angle of light emission. Thus light entering the bases of the prisms and traversing the interior thereof will strike both the outer or emissive surfaces of the prisms, but will all be emitted from one of them only. As all of these emissive surfaces are presented in one direction all light falling on the interior of the lower hemisphere will be emitted downwardly.

With the angles which I have above described, the above result will follow any displacement of the light below the equatorial plane, and a similar effect will be produced even if the light be somewhat displaced from the exact polar axis of the container. It will be evident, however, that similarly operating prism angles having the characteristic single reflection followed by emission as to part of the light, and double reflection followed by emission on the same side as to another portion of the light, may be achieved by prisms which are not exactly isosceles and in containers which are not exactly hemispherical.

I have described the container thus far as hemispherical only, and it is obvious that the upper portion of the container may also be similarly and symmetrically hemispherical although for practical reasons, especially in the case of arc lights, the upper hemisphere may be omitted or may be given other than hemispherical shapes, or a reflector, preferably concave, might be used.

By reference to the angle of the refractor,

I do not mean necessarily the angle at which the outer faces meet, as the outer edge of the refractor may be truncated or rounded off, but I do mean the angle at which the major portions of the faces lie in respect to each other. These faces may be very slightly curved either concave or convex, and commercially satisfactory results may still be obtained. I have mentioned the angle as being $32^{\circ} 34'$ and this is substantially correct for glass having an index of refraction of 1.52, but it is evident that with variations in the index there must be a corresponding change in the angle for the most efficient results. Furthermore, this angle is not the only possible one for a given glass but is merely the most efficient one. As the angle of the faces decreases or increases from this, the range or space within which the source of light must be located, for efficient directing action, decreases. Efficient results may be obtained through a variation of several degrees each way from $32^{\circ} 34'$ for glass of 1.52 index of refraction and in special cases there may be quite a wide divergence, but much of a departure from the angle $32^{\circ} 34'$ causes the results to be seriously modified.

My invention is particularly useful in connection with overhead lights, the refractors being arranged to encircle and extend beneath the source of light. The source of light and refractors are so positioned in respect to each other and the refractors are so formed that the source of light will be below the bisector of the outer angle of each refractor and each refractor will emit substantially all of the light received by it downwardly from its lower face and all of the refractors will emit light in the same hemispherical direction—that is to say, substantially all the light will radiate in one hemispherical region lying on one side of a horizontal plane passing through the top of the lamp. Furthermore, these refractors may be properly formed and arranged to secure this result, and, at the same time, all or substantially all of the light emitted from each refractor will clear the outermost portion or tip of the adjacent refractor below it. To secure downward distribution, the source of light should be below the bisector of angle between the outer sides of each refractor, so that a larger part of the light will strike the upper face of the refractor than strikes the lower. It is only important that the bisector of the angle pass on the opposite side of the source of light from that in which it is desired to direct the light, so far as concerns the case of the isosceles triangle prisms, in which such bisector is always perpendicular to the base, but in designing any modifications within the spirit of my invention, the angle of the light after it has entered the base and been refracted and while it is traversing the interior of the

prism should be considered with reference to such bisector.

In the drawings: Figure 1 is a diagrammatic representation of a section through a spherical container with lines representing certain light rays from a source of light in two different positions. Fig. 2 is a central longitudinal section through a portion of a container the source of light being conventionally represented as an arc light. Fig. 3 is a side elevation of the container shown in Fig. 2.

The diagram forming Fig. 1 of the drawing represents a central vertical section through a spherical container 10 with a series of refractors 11 upon its outer surface. The center of the container is at the point 12 and a source of light is represented in two different positions 13 and 14. The refractors are of isosceles form in cross section, that is the bisector of the angle between the two outer sides of each refractor passes through the center point 12 and such bisectors are coincident with lines normal to the bases of the several refractors at their centers. The source of light when at the point 13 will have its rays 13^a and 13^b entering the base of each refractor and the lower ray 13^a will strike the lower surface 11^a of a refractor and the ray 13^b will strike the upper surface 11^b. As the source of light is below the center of the sphere the angle of intersection of the ray 13^a and surface 11^a will be more acute than the angle between the upper ray and the upper surface. By forming the refractors with their outer surfaces at the proper angle, which angle is substantially 32° and 34° for a glass having an index of refraction of 1.52 the light ray 13^a will be totally reflected by the surface 11^a and will pass upwardly toward the upper surface 11^b. Here it will be totally reflected a second time and pass downwardly toward the surface 11^a, this time striking the latter at such an angle that it will emerge in a direction upon the same side of the bisector of the angle as is the source of light. The light ray 13^b will strike the surface 11^b at a steeper angle, but will nevertheless be totally reflected within the refractor and pass toward the surface 11^a. Here it will emerge in the same general direction as those light rays corresponding to the light ray 13^a and which were doubly reflected. Thus all of the light which enters the base will be either singly reflected within the refractor or will be doubly reflected and all of said light will emerge on the same side of the bisector of the angle as is the source of light. As the refractors encircle the container it will be noted that all of the light rays striking the lower or hemispherical portion will emerge in a general downward direction and the light which strikes some of the refractors

above the plane of the equatorial diameter will also be directed downwardly. Furthermore, it will be noted that the light downwardly directed by each refractor will clear the apex of the next lower refractor. I have only discussed the light rays from the point 13 which is only a short distance below the center of the sphere, but it will be noted that rays 14^a and 14^b coming from a lower source 14 will be directed in the same manner. It is thus evident that the exact position of the source is immaterial so long as it is in or substantially in the polar diameter *c-d* and below the plane of the equatorial diameter *e-f*. Experiment will readily show the particular distance below at which the best results are obtained, but if the source of light be positioned at a point corresponding to either of the points 13 or 14 or anywhere between the two points, or in their immediate vicinity, satisfactory results will be obtained.

In Figs. 2 and 3 I have illustrated a container 15, to a certain extent conventionally, and constituting a practical embodiment of my invention, but to avoid confusion I have illustrated the refractors 16 on a much larger scale proportionally, than is necessary in practice. I do not wish to be limited in any way to any particular size of refractor or any particular number of refractors, nor any particular mode or method of forming the container, and the refractors. In my prior Patent 1,036,527, issued August 20, 1912, I have disclosed a method of forming a series of ridges and grooves by first coating the outer surface of the container with a suitable wax preparation and marking or cutting grooves through this coating and along which the glass may be etched away by chemical or embrasive action preferably by hydrofluoric acid. If the refractors of my present invention be formed very minute substantially the same method might be employed for forming them, or if they are to be made larger they may be formed by mechanical grinding or cutting away the glass to leave the refractors of the particular shape or the glass container may be molded with the refractors thereon.

In Fig. 2 the source of light is conventionally illustrated as an arc light 17, but as I have previously pointed out, any well known source of light may be employed. I have also illustrated the upper portion 18 of the container of substantially cylindrical form with symmetrical refractors thereon. For a short cylinder length it is evident that the refractors thereon will all act to direct the light downwardly.

It will be evident that while I have shown and described and have even specified in certain of the claims that the bisectors of the ridge angles of the refractors pass through the center of curvature of the

sphere, I do not thereby mean to limit myself to a mathematically exact device, the construction of which would be prohibitively expensive. The same thing is true 5 as to claims in which I specify the exact number of degrees of the angle of convergence of the outer surface of the prisms. Similarly, also, it will be understood that while I refer to the source of light or the 10 center of luminosity as being "below" the region of convergence of the bisectors of the ridge angles, the word "below" does not necessarily have any particular significance with respect to the direction of pull of gravity but is merely used as a convenience for 15 making clear the novel relative position and relation of the light with reference to the refractors.

Having thus described my invention, 20 what I claim as new and desire to secure by Letters Patent is:—

1. A transparent wall having refractors in the form of approximately parallel prismatic ridges on the outer surface, each ridge 25 being of triangular cross section throughout its extent and each having the straight line elements forming its two outer surfaces converging toward the summit of the ridge at an angle of such acuteness as to internally 30 reflect all rays falling upon said surfaces through the base of the refractor, and to emit the same after at least one and not more than two such reflections, in combination with means for radiating light upon the 35 rear of said transparent wall from points eccentric to the region of convergence of the bisectors of the ridge angles of said converging surfaces.

2. In combination, a source of light and 40 an encircling transparent wall having refractors in the form of approximately parallel prismatic ridges on its outer surface, each ridge being of substantially the same cross section throughout its extent and each having 45 its two outer surfaces converging toward the summit of the ridge at an angle of such acuteness as to internally reflect all rays falling upon said surfaces through the base of the refractor, and to emit the 50 same after one or more such reflections, said source of light being located on the other side of said wall, below the region of convergence of the bisectors of the ridge angle of said converging outer surfaces, whereby 55 substantially all of the emitted light is deflected in the same direction.

3. A spherically curved transparent wall having refractors in the form of approximately prismatic ridges on its outer surface, 60 each ridge being of substantially the same cross section throughout its extent and each having its two outer surfaces converging toward the summit of the ridge at an angle of such acuteness as to internally reflect all rays

falling upon said surfaces through the base 65 of the refractor, and to emit said rays after one or more such internal reflections, each of said ribs having its said outer surfaces disposed so that all bisectors of the ridge angles of all of the ridges pass through or 70 above the center of curvature of said spherical wall, in combination with a source of light having its center of luminosity located near the common axis of all said ridges and below said center of spherical curvature. 75

4. A transparent wall having prismatic refractors in the form of approximately parallel ridges on its outer surface, each ridge being of substantially the same cross section throughout its extent and each having its 80 two outer surfaces converging toward the summit of the ridge at an angle which is substantially the equivalent of an angle of thirty-two degrees and thirty-four minutes for glass having an index of refraction at 85 one and fifty-two hundredths, thereby internally reflecting all rays falling upon said surfaces through the base of the refractor and emitting the same after one or more such reflections. 90

5. A transparent wall having prismatic refractors in the form of approximately parallel ridges, each ridge being of substantially the same cross section throughout its extent and each having its two outer surfaces converging toward the summit of the ridge at an angle which is substantially the equivalent of an angle of thirty-two degrees and thirty-four minutes for glass having an index of refraction at one and fifty-two hundredths, thereby internally reflecting all rays falling upon said surfaces through the base of the refractor and emitting the same after one or more such reflections, in combination with a source of light located below the 105 region of convergence of the bisectors of the ridge angle of said converging outer surfaces whereby substantially all of the emitted light is deflected in the same direction. 100

6. In combination, a source of light and an encircling spherically curved transparent wall having prismatic refractors in the form of approximately parallel ridges, each ridge being of substantially the same cross section 115 throughout its extent and each having its two outer surfaces converging toward the summit of the ridge at an angle which is substantially the equivalent of an angle of thirty-two degrees and thirty-four minutes 120 for glass having an index of refraction at one and fifty-two hundredths, thereby internally reflecting all rays falling upon said surfaces through the base of the refractor, and emitting said rays after one or more 125 such internal reflections, each of said ribs having its said outer surfaces disposed so that all bisectors of the ridge angles of all

of the ridges pass through the center of curvature of said spherical wall, said source of light being located in the common axis of all said ridges and below said center of spherical curvature, whereby substantially all the light emitted from said wall is deflected downwardly.

Signed at New York city, in the county of New York and State of New York, this 14th day of December, A. D. 1912.
